UNITED STATES PATENT OFFICE.

AXEL ANDERSON, OF STAVE FALLS, BRITISH COLUMBIA, CANADA.

CRATE.

1,211,656.

Specification of Letters Patent.

Patented Jan. 9, 1917.

Application filed May 29, 1915. Serial No. 31,304.

To all whom it may concern:

Be it known that I, AXEL ANDERSON, a citizen of Sweden, residing at Stave Falls, in the Province of British Columbia, in the 5 Dominion of Canada, have invented certain new and useful Improvements in Crates, of which the following is a specification.

This invention relates to improvements in crates of the folding or collapsible type and 10 its object is to produce a crate of this class in which the side and end members are provided with metal cleats of an interlocking type whereby said members may be extended and adjustably locked in such position in- 15stantaneously.

Simplicity in construction and cheapness of manufacture are other objects.

With the foregoing and other objects in view the invention consists in the combination 20 and arrangement of parts to be herein-after fully described in the following specification, pointed out in the claims and illustrated in the accompanying drawings which form a part of said specification and in 25 which—

Figure 1 is a plan view of my improved crate. Fig. 2 is a side elevation of the same. Fig. 3 is a sectional detail taken on line 3—3 of Fig. 1. Fig. 4 is an end view 30 of the crate. Fig. 5 is a section taken on line 5—5 of Fig. 6. Fig. 6 is a cross section taken on line 6—6 of Fig. 2. Fig. 7 is a longitudinal sectional view taken on line 7—7 of Fig. 4. Fig. 8 is an end view 35 of the crate folded. Fig. 9 is a side view of the folded crate.

Like reference characters indicate corresponding parts throughout the several views.

The reference character 1 designates the 40 base of the crate to which the band 2 is secured, the ends of the band being disposed upon the upper or inner side of the base and apertured as at 3 in alignment with notches or recesses in the lateral edges of the base.

45 The base 1 is provided, further, with the terminal bands 4, 4 that extend entirely across the under side of the base and up above the same, the upper ends of the same being pivotally secured as at 5^a to the metallic bands 5 that cover the lateral edges of the end pieces 6 which pieces are supported by the said pivots 5^a. The bands 5 of the end pieces are projected inwardly along said pieces and spaced away therefrom as at 7.

55 The terminal bands 4 of the base are formed with inwardly projected fingers 8 that are

connected by pivots 9 to the projection 10 which is spaced away from the end edge of the side member 11 and which is an integral part or projection of the band 12 which is 60 secured to the inner face of the said member 11; the pivots 9 aforesaid serving as supports for the said side members 11. Each side member 11 is provided with a screw 13 adapted to register with the opening 3 in 65 the band 2 and which screw may be adjusted with relation to said side member to cause frictional engagement with the base 1 to help retain said side member in adjusted relation. Each end member is provided with 70 a similar screw adapted to a like purpose in connection with an apertured end brace 14. One end piece 6 is provided with a band 15 along its upper edge which band is formed with an upturned edge adapted to receive the spaced edge 16 of the band 17 carried by one end edge of the top 18; the opposite end edge of the said top being covered by a band 19 which, together with said top, is formed with threaded openings in alignment with similar openings in the upper edge of the adjacent end piece 6 adapted to receive screws 20 whereby said top and end piece may be secured together. One end piece 6 is provided with the headed pins 21 85 and the other end piece 6 with the apertured plates 22, the apertures in which are in alignment with threaded apertures in the said end piece and which are adapted to receive the screws 20 when the crate is in collapsed 90 position.

In Fig. 1 the crate is in assembled position. To collapse the same the top is removed by removing the screws 20 and then removing the loose edge of the band 17 from the band carried upon the upper edge of the adjacent end piece 6. The side pieces 11 are now forced toward each other upon their pivots 9 thus withdrawing the interlocking edges 10 of the bands 12 from engagement 95 with the edges 7 of the bands 5; the sides will fold one upon the other on the base 1. The end pieces 6 are now forced toward each other upon their pivots 5^a and the cover 18 is now placed upon said end pieces, the screws 20 being turned into the apertured plates 22 and the spaced edge 16 of the band 17 engaging with the headed pins 21; the crate is now collapsed and ready for shipment as an empty.

What is claimed is:—

1. A crate comprising a base, terminal

bands carried by said base and projected upwardly therebeyond, end pieces, bands for the edges of said end pieces formed with inwardly projected portions spaced from the 5 inner sides of said end pieces, fingers projected inwardly from the said terminal bands and through the bands applied to the edges of said end pieces, said end pieces being pivotally carried by said fingers, side 10 pieces, terminal bands for said side pieces formed with projections spaced from the ends of said side pieces and adapted for interlocking engagement with the first named projected portions whereby said end and 15 side portions are retained in assembled relation and a top adapted for releasable locking engagement with the said end pieces.

2. A crate comprising a base, terminal bands carried by said base and projected upwardly therebeyond, end pieces, bands for the lateral edges of said end pieces formed with inwardly projected portions spaced from the inner sides of said end pieces, fingers projected inwardly from one of the 20 said bands and through the other of said 25

bands, apertured plates carried by one of said end pieces, headed pins carried by the other end piece, side pieces pivotally carried by said fingers, bands carried by the side faces of said side pieces and formed with 30 projections extending along and spaced from the end edges thereof for interlocking engagement with the first named projections whereby said end and lateral pieces are retained in assembled relation and a top provided with means for releasable engagement with the said end pieces when in assembled relation and for releasable engagement with the said apertured plates of one end piece and with the headed pins of the other end 35 piece when said members are in collapsed relation.

In testimony that I claim the foregoing as my own I have hereto affixed my signature in the presence of two subscribing witnesses. 40 45

AXEL ANDERSON.
